BUTTON LOOP

Application filed June 28, 1929. Serial No. 374,399.

This invention relates to button loops constructed in two parts, a loop proper and a button retaining member depending therefrom, the device being employed to connect 5 a strap with a button carried by a garment, or the like, intended to be supported by the strap.

The objects of the invention are to provide a simple means of connecting a button retaining member with the loop proper to permit the independent expansion of both members; and to provide a two-part button loop the members of which are relatively fixed against pivotal movement.

15 The invention consists in the novel constructions, to be hereinafter described or claimed, for carrying out the above stated objects, and such other objects as may hereinafter appear.

20 The character of the invention may be best understood by reference to one illustrative device embodying the invention and illustrated by the figures in the accompanying drawing in which the Figure 1 is an elevation 25 of a two-part button loop in a normally contracted condition; and the Figure 2 is a similar elevation, but illustrating the button loop in an expanded condition.

The invention is not limited to any specific 30 form of construction and the details of the device may be varied to produce the novel features hereinafter claimed, the device as illustrated, however, is a two-part button loop of which the loop proper provides a suspension loop 1, a button receiving loop or eye 2, a normally contracted throat portion 3, and depending arms 4 and 5 providing attaching means 6 and 7 for engagement with the other member which provides a second 35 normally contracted throat portion 8 and the button retaining loop 9. The button loop proper is preferably formed of a piece of resilient wire a middle portion of which is bent to form the suspension loop 1, the remaining end portions of the wire depending from the suspension loop 1 to provide the side arms 4 and 5 forming the button receiving loop 2 and the contracted throat portion 3, the wire extremities then diverging to form 40 the laterally spaced looped ends 6 and 7

formed in a plane perpendicular to the plane of the button loop. The button retaining member is preferably formed of a piece of resilient wire the middle portion of which is bent to form the retaining loop 9, and the remaining end portions are bent inwardly to form the contracted throat 8, one of the novel features of novelty of which this invention constitutes, the end portions then diverging and the wire extremities being formed into the elongated loops 10 and 11 lying in the plane of the button retaining loop. The manner of connecting the two parts of the device forms another of the features of novelty of the invention. In inter-looping the attaching loops 6 and 7 with the lower bar portions of the loops 10 and 11, respectively, the arm 4 is made to snugly engage one side of the upper bar of the loop 10 while the arm 5 is made to snugly engage the reverse side of the upper bar of the loop 11 to maintain a rigid assembly as regards relative pivotal movement, but permitting a relative sliding movement in both lateral directions, each of the loops 10 and 11, in its interlooped engagement with the respective loops 4 and 5, being adapted to normally rest intermediately as regards the elongated loops.

A button being received within the loop 2, the button shank 12, resting in the position illustrated by the Figure 1, may be urged downwardly to operate and expand the throat portion 3 as illustrated by the Figure 2. It is obvious that the shank 12 may be further urged to likewise operate and expand the throat portion 8 and assume its final position within the retaining loop 9 behind the two contracted throats, the resiliency of the wire forming each part being relied upon to return the throat portions to their normally contracted condition. The reverse action upon the release of the shank 12 from behind the contracted throats 8 and 3 is, of course, similar to that already explained with regard to the entrance of the shank 12 to the retaining loop 9, and, in both instances of entrance and release, the movement of the device along its plane may, of course, be substituted for the forced movement of the button, the relative 50 55 60 65 70 75 80 85 90 95 100

rigidity of the assembled parts against pivotal movement being advantageous for this purpose.

I claim:

- 5 1. A button loop comprising a suspension member having an open button receiving eye terminating in an expansible contracted throat and diverging ends, a button retaining member, and looped connections provided by the members and permitting a relative lateral sliding movement, the connection including stops maintaining the members relatively rigid against pivotal movement.
- 10 2. A button loop comprising a suspension member having an open button receiving eye terminating in an expansible contracted throat and diverging ends, a button retaining member having an expansible contracted throat and diverging ends, and looped connections provided by the diverging ends of both members and permitting a relative lateral sliding movement, the connection including stops maintaining the members relatively rigid against pivotal movement.
- 15 3. A button loop comprising a suspension member having an open button receiving eye terminating in an expansible contracted throat and diverging ends, a button retaining member having an expansible contracted throat and diverging ends, and connecting means provided by the diverging ends of both members and permitting a relative lateral sliding movement, the means including stops rigidly maintaining the members against relative pivotal movement.
- 20 4. A button loop comprising a suspension member of resilient wire and having an open button receiving eye terminating in a normally contracted throat and diverging ends looped in a plane perpendicular to that of the member, and a button retaining member of resilient wire and having a normally contracted throat and diverging ends with elongated loops in the plane of the member but
- 25 at right angles with the other end loops, the end loops of one member being so interlooped with the end loops of the other member that one of the diverging ends of the suspension member provides a stop preventing a relative movement of the members in one pivotal direction and the other diverging end of the suspension member provides a stop preventing a relative movement of the members in the opposite pivotal direction, the
- 30 stops maintaining the members relatively rigid against all pivotal movement.

ROBERT J. HODGE.
